No. 37,241.

Patented November 22, 1904.

UNITED STATES PATENT OFFICE.

PAUL MARGOLIS AND HENRY METZGER, OF KANSAS CITY, MISSOURI.

DESIGN FOR A SPOON, FORK, OR SIMILAR ARTICLE.

SPECIFICATION forming part of Design No. 37,241, dated November 22, 1904.

Application filed October 17, 1904. Serial No. 228,907. Term of patent 3½ years.

To all whom it may concern:

Be it known that we, PAUL MARGOLIS and HENRY METZGER, citizens of the United States, residing at Kansas City, in the county of Jackson, State of Missouri, have invented a new, original, and ornamental Design for Spoons, Forks, or Similar Articles, of which the following is a specification.

Our new design is represented in the accompanying drawing, wherein is shown a

perspective view of a spoon or fork embodying our design.

What we claim is—

The ornamental design for a spoon, fork, or similar article, as shown.

PAUL MARGOLIS.
HENRY METZGER.
